UNITED STATES PATENT OFFICE.

JACOB P. TETER, OF INDIANAPOLIS, INDIANA.

DEHYDRATOR FOR CLAY SLIPS.

Application filed April 19, 1924. Serial No. 707,789.

This invention relates to a device for separating the constituents of a liquid mixture, and herein the device illustrated is adapted particularly for the separation of china clay from clay slip solution.

The chief object of the invention is to construct a device which will economically and most expeditiously separate clay from a clay slip solution.

Another object of the invention is to dry the material separated from the liquid portion in order to obtain material in dry powder form.

The chief feature of the invention consists in the structural arrangement of the main separator or dehydrator unit which herein is illustrated as of the centrifugally separated type.

The full nature of the invention will be understood from the accompanying drawings and the following description and claims:

In the drawings, Fig. 1 is an enlarged central sectional view of the invention showing the complete separator and drier. Fig. 2 is an elevational view of a portion of the combination scraper and conveyor construction included in the separator. Fig. 3 is a transverse sectional view taken on the line 3—3 of Fig. 1 and in the direction of the arrows and illustrates particularly the agitator construction.

In the drawings there is illustrated a base 10 including an offset bracket portion 11 and a diverging upturned supporting bowl 12. The extreme end of the bowl 12 is apertured at 13 and supported by the same is a tube 14 that in turn supports an annular plate 15, said plate being rigidly mounted upon the base construction previously described, by means of the bolt 16 and the nuts 17. Any other suitable form of mounting, however, may be utilized without departing from the invention. Depending from the annular plate 15 which also forms a cover for a construction hereinafter to be described is a shell 18 having an outwardly directed lateral flange 19, whereby the same is supported upon the annular plate 15. Positioned axially within said shell 18 is a tube 20 which is connected to a pipe or supply line 21 controlled by a valve 22. Herein the aforesaid construction is all stationarily mounted with respect to each other.

In the framework thus formed, there is mounted, co-axially with the central axis

previously indicated, a tube 23 which has a telescopic connection with the tube 20 and which also is rotatably associated therewith. The tube 23 at its lower end is supported by a bowl 24 centrally apertured at 25 to receive the same. Positioned beneath said bowl and in nested but spaced relation therewith is another bowl 26. The bowl 26 includes an apertured central portion 27. A shaft 28 is suitably secured therein and extends downwardly therefrom through the angular bracket 11 and carries in the offset portion of said bracket a power member 29. The shaft 28 is enlarged at 30, which enlargement forms an abutment with which cooperates the securing nut 31, whereby the bowl 26 is rigidly mounted upon the shaft 28 and is rotatable therewith. Suitable anti-friction bearing constructions 32, 33 and 34 are provided and are associated with the shaft construction. The shaft 28 is extended upwardly into the tubular member 23 as at 35 and a worm or spiral agitator and conveyor 36 is carried thereby. Interposed between the bowls 24 and 26 and maintaining the same in spaced relation are a plurality of arms 37, which arms, as shown, not only conform to the curvature of the bowl space but also are curved with respect to the radius of said bowl. These vanes 37 in the present instance terminate short of the annular mouth 38 of the rotatable bowl construction. The separating deflectors 9 are positioned in the annular mouth and assist in deflection.

From the foregoing, therefore, it will be apparent that the clay slip mixture, such as china clay in water solution may be supplied to the tube 23 at the desired rate through the valve controlled line 21. The solution in the tube is agitated by the spiral 36 and is forced through the bowl space to the annular bowl discharge 38 by centrifugal force. The solution, therefore, is discharged upwardly and outwardly, and by means of the curved blades or vanes 37 a whirling action is imparted to the material. Likewise, the flow may be varied so that the device may satisfactorily operate upon mixtures of different specific gravities.

Concentric with the depending shell 18 which terminates at its bottom relatively close to the mouth 38, there is provided a screen construction including a coarse screen 40, a finer screen 41 within the same, a still finer fabric screen 42 protected by a

fine screen or bolt cloth 43. The screens 41 and 43 may be alike if desired. As the solution discharges from the annular mouth 38 by means of the deflectors upwardly and 5 outwardly into the annular channel formed by the shell 18 and the annular concentric screen construction previously described, the material passes through the screen and discharges against an outer shell 44. The 10 liquid thus discharged drains downwardly and is collected by the collector ring or open tube drain construction 45. It will be understood that the screen construction previously described is suitably secured to the 15 bowl construction, and, therefore, is rotatable therewith. As the material continues to discharge, there is gradually separated from the same the clay which fills the small perforations or interstices of the inner 20 screen 43, it being retained in said perforations by the bolt cloth or similar suitable material interposed between the two fine screens. After the perforations or interstices have been filled with the clay material, 25 there is formed upon the inner screen a layer of clay material. This clay material is porous and thus after the device has been once started, the material separated forms a portion of the filter by forming a filter layer 30 46 within the rotatable screen construction and is rotatable thereby. This layer continues to build up in thickness and would continue to do so until the annular passage became choked. However, suitable scraping 35 means is provided which is adapted to maintain the clay filter layer at a predetermined thickness and convey the surplus from the annular passage. This combination 40 scraper and conveyor or elevator construction, as shown clearly in Figs. 1 and 2, includes not only the shell 18 but also a plurality of offset angle plates 47 suitably secured to said shell. As the screen construction rotates, the clay material separated by 45 the same is gradually worked upwardly until it engages the topmost row of the sepa-

rators 47, whereupon it is automatically discharged into a collecting trough 48, which trough is stationary.

A conduit 49 connects said trough 48 with a drier portion 50 which is enclosed by a jacket construction 51 supplied by a valve controlled line 52 adapted to supply a heating medium to the jacket. The jacket may be drained through the valve construction 53. A fan construction 54 is associated with the discharge line 55 connected to the drier line 50 and thus the dried and powdered material may be transported through the drier. Generally the material as discharged into 60 the line 49 is sufficiently dry and powdered for further operation, but if a greater degree of dryness is desired, the additional drier construction herein illustrated may be utilized. It will, of course, be understood 65 that the waste trough 45 discharges through a suitable connection, such as 45^a in Fig. 3.

The invention claimed is:

1. A dehydrator comprising a rotatable annular filtering wall, a second and stationary wall in spaced relation therewith forming an annular channel therebetween, means on the second wall for causing longitudinal or axial movement of the filtered solids, an annular receiver adjacent the top of the filtering wall into which the solids are discharged by said means, a pair of bowls beneath said walls and in spaced relation with each other forming a channel communicating with the first mentioned annular channel, means for supplying filtering material to said bowl channel, and means for rotating said bowls and said rotating wall for dehydrating said material.

2. A device as defined by claim 1, characterized by the addition of a plurality of deflectors connecting said bowls, each deflector extending radially outward and being curved from end to end.

In witness whereof, I have hereunto affixed my signature.

JACOB P. TETER.
